DESIGN FOR A JAR COUPLING FOR HOLDING PAINT BRUSHES

Titus Oliver Fredell, Minneapolis, Minn.

Application May 1, 1945, Serial No. 119,333

Term of patent 14 years

(Cl. D58—25)

To all whom it may concern:

Be it known that I, Titus Oliver Fredell, a citizen of the United States, residing at Minneapolis, in the county of Hennepin and State of Minnesota, have invented a new, original, and ornamental Design for a Jar Coupling for Holding Paint Brushes, of which the following is a specification, reference being had to the accompanying drawing, forming part thereof.

Figure 1 is a front elevation of a jar coupling

for holding paint brushes showing my new design,

Figure 2 is a top plan view of the invention.

Figure 3 is a section through a portion thereof taken on the line 3—3, Figure 2.

I claim:

The ornamental design for a jar coupling for holding paint brushes, as shown.

TITUS OLIVER FREDELL.
